[57] CLAIM

The ornamental design for holster for portable telephone and other electronic equipment, as shown and described.

DESCRIPTION

FIG. 1 is a front elevational view of a holster for portable telephone and other electronic equipment on a human figure, showing our new design;

FIG. 2 is a front elevational view thereof similar to FIG. 1 without the human figure;

FIG. 3 is a side elevational view thereof taken from the left side in FIG. 2;

FIG. 4 is side elevational view thereof taken from the right side in FIG. 2;

FIG. 5 is a top plan view thereof;

FIG. 6 is a rear elevational view thereof;

FIG. 7 is a front elevational view of an alternate embodiment on a human figure;

FIG. 8 is a front elevational view thereof similar to FIG. 7 without the human figure;

FIG. 9 is a side elevational view thereof taken from the left side in FIG. 8;

FIG. 10 is a side elevational view thereof taken from the right side in FIG. 8;

FIG. 11 is a top plan view thereof; and,

FIG. 12 is a rear elevational view thereof.

The human figure and phone are shown in broken lines for illustrative purposes only and form no part of the claimed design.
